UNITED STATES PATENT OFFICE.

WILLIAM E. SMITH, OF MILLTOWN, NEW JERSEY, ASSIGNOR TO GULBENKIAN SEAMLESS RUG COMPANY, OF NEW BRUNSWICK, NEW JERSEY, A CORPORATION OF NEW JERSEY.

PILE-WIRE-CONTROLLING MECHANISM FOR LOOMS.

Application filed January 27, 1925. Serial No. 5,041.

The object of my invention is to improve the pile wire controlling mechanism of carpet weaving looms and especially that type of loom on which is woven seamless rugs of the larger proportions, with a view of eliminating the so-called "smash," common to this type of loom, such as result from the misplacement of a pile wire in the open warp shed of the fabric being woven, by the wire controlling mechanism.

The wire controlling mechanism employed on looms in general use at the present time comprises a wire switch and a wire carriage reciprocally mounted on a rail secured to the frame of the loom.

The wire carriage is moved in one direction, to withdraw a pile wire from the woven fabric, by an endless chain belt and in a reverse direction, to insert a pile wire into the open pile warp shed of the fabric being woven, by a rope and spiral wheel motion well known to those familiar with the art.

The rope and spiral wheel motion employs mechanism including a friction clutch which is extremely unreliable in operation, difficult to adjust and maintain in adjustment and is therefore responsible for a large percentage of the costly loom stoppages, so well known to those engaged in the manufacture of textile fabrics produced on looms of this general type.

Should a drop of oil enter between the engaging elements of the said friction clutch, or should a slight amount of additional friction develop between the wire carriage and the rail on which it reciprocates, or should a change of temperature affect the length of the rope of such motion, the wire being inserted into the open warp shed of the fabric being woven will be misplaced with respect thereto, by reason of the clutch slipping or the variation in the length of the rope. Such misplacement usually consists of the wire not being fully inserted and the shed closing on the knife end of the wire, with a resultant cutting of the warp threads commonly designated as a "smash".

One of the essential features of my invention is to replace the above mentioned unreliable friction clutch and all the other operating and controlling elements of the rope and spiral wheel motion, with mechanism of a positive operating nature, which will be

fully described in the body of the following specification.

On this larger type of loom, the pile wires are "beat up" into the carpet in the usual manner, but, due to the large number of warp threads formed into loops around each of the pile wires, it is extremely difficult to withdraw a wire from the woven carpet. As the pile wire is withdrawn, the knife, formed on one end of the same, cuts the engaging pile warp thread loops, to form the cut pile face of the carpet.

The carriage overhangs the rail and switch at one of its sides on which is mounted a wire engaging hook, offset from the centre line of the operating chain and in line with the pile wire to be withdrawn, the said overhanging portion of the carriage also enters a slot in the head of the engaged wire in a manner and for a purpose well known in the art.

The enormous amount of power required to withdraw a pile wire, against the frictional engagement between the pile wire and the pile warp threads, causes the carriage to raise at its overhanging side, as the pile wire is withdrawn, thereby raising the head end of the pile wire from the bottom of the switch groove. Such raising of the head of the pile wire causes the said wire to flex or bow vertically.

When the carriage is moved in its reverse direction, to insert the previously withdrawn pile wire, the said flexing of the body of the same, causes the knife end of the pile wire to be diverted from a straight line course, the said knife end fouling the warp threads of the open shed and thereby cutting said pile warp threads to a more or less serious extent. This condition is also commonly termed a "smash", in the art, and is primarily caused by the said flexing of the pile wire, when it is inserted into the open pile warp shed by the pile wire controlling mechanism.

Considerable time is required, wherein the loom is inoperative, to repair the resultant damage of the so-called "smash".

Another essential feature of my invention is to provide mechanism by which the raising of the overhanging side of the pile wire carriage is arrested immediately after the initial movement of the carriage and the pile

wire, with respect to the woven carpet, and the pile wire is returned to the bottom of the switch groove wherein it is maintained throughout the remainder of its travel outwardly, and also throughout its entire inward travel whereby it is projected through the open pile warp shed in a straight course avoiding contact with the threads forming such shed. The shed then changes and the lay of the loom "beats up" the wire in the usual manner.

Other advantages pertaining to the details of construction of my improved pile wire controlling mechanism will be fully disclosed in the specification and shown in the accompanying drawings, wherein:

Figs. 1 and 2 are respectively diagrammatic plan and front elevational view of sufficient of a loom to illustrate the operation 20 of my invention as applied thereto.

Fig. 3 is an enlarged plan view of the carriage and its associated elements;

Fig. 4 is a sectional elevation taken on the line 4—4, Fig. 3;

Fig. 5 is a sectional elevation taken on the line 5—5, Fig. 3;

Fig. 6 is a sectional elevation taken on the line 6—6, Fig. 3;

Fig. 7 is a sectional elevation taken on the line 7—7, Fig. 3.

Fig. 8 is an enlarged front elevation of the outer end of the carriage rail with certain of the carriage controlling elements mounted thereon and showing the carriage as having completed its outward travel;

Fig. 9 is a transverse sectional elevation taken on the line 9—9, Fig. 8;

Fig. 10 is a transverse sectional elevation taken on the line 10—10, Fig. 8;

Fig. 11 is a sectional elevation taken on the line 11—11, Fig. 9;

Fig. 12 is a rear elevation of the mechanism shown in Fig. 8, the carriage in this instance being considered as having completed its inward travel;

Figs. 13, 14, and 14^a are perspective views of certain details of the invention as shown in Figs. 11 and 12 respectively;

Fig. 15 is a sectional view taken on the line 50 15—15, Fig. 9;

Fig. 16 is a fragmentary elevation of a special idler sprocket wheel employed in my pile wire controlling mechanism; and

Figs. 17 and 18 are sectional views taken 55 on the lines 17—17 and 18—18, respectively, Fig. 16.

Referring to Figs. 1 and 2, the loom is illustrated at *a*; the pile wire controlling mechanism at *b*; the pile wires at *c* and the pile wire carriage at *d*.

The open pile warp shed is illustrated at *e*; the beat up uncut pile face of the carpet with the pile wires therein is shown at *f*; and the cut pile face of the carpet is illustrated at *g*.

The pile wire controlling mechanism *b* consists of the usual substantially U-shaped rail or track 1 and a switch tongue 2, pivoted to the rail at 3.

The vertical walls of the rail 1 are grooved as at 4 for the reception of laterally and longitudinally extending ribs 5 of a slide block 6, of the carriage *d*. A plate 7 is secured, adjacent one of its sides, to the slide block 6 by stud bolts as shown in Fig. 7. The plate 7 of the carriage *d* overhangs the switch 2 at its side opposite the rail 1, and has pivotally secured thereto a hook 8 for engaging the pile wires *c*, successively. A bracket 9 is also secured to the plate 7 by the said stud bolts and provides a support for one end of each of a pair of pivot bolts 10 and 11, on which are respectively mounted a dog 12 and a retaining lever 13. The opposite ends of the bolts 10 and 11 are supported in a vertical flange 14 of the plate 7. The lever 13 is resiliently held in engagement with the dog 12 by a spring 15, (Fig. 3). The dog 12 is adapted to be engaged by a lug 16 on one link of a link belt 17, which runs in the rail 1 in the usual manner as shown in Fig. 4 of the drawings.

The link belt 17 is driven by a sprocket wheel 18 and passes around idler wheels 19—19 and 20—20 in the usual manner as clearly shown in Fig. 2, for the purpose of engaging the carriage *d* and moving it so as to withdraw successive pile wires from the carpet.

At the end of the outward travel of the carriage *d*, a projecting end of the lever 13 is engaged by a trip 21 on the rail 1, and the dog 12 is thereby released from the link belt 17 and the carriage stopped; at which time the free end of the switch tongue 2 is moved from its pile wire withdrawing position to its pile wire inserting position. The pile wire inserting motion then becomes operative to move the pile wire and the carriage in a direction to reinsert the said pile wire into the open warp shed.

Mounted on the vertical flange 14 and secured thereto by the bolts 11 and 12 is a bearing member 31 having thereon a pair of horizontally and axially aligned bearings 22 and 23. Slidably mounted in the said bearings 22 and 23 is a rod 24, shouldered as shown for engagement with a loosely mounted collar 26 having projecting lugs 27 and 28 integral therewith. The collar 26 is held in contact with the inner end of the bearing 23 by a spring 29 which encircles the outer end of the rod 24 and is adjustably confined between the outer end of the bearing 23 and a pair of collars 30—30 adapted to a screw threaded end of the rod 24.

The lug 27 of the collar 26 is undercut opposite the bearing 23, for engagement by a hooked end 32 of a latch 33. The latch 33 is pivoted at 34 to the bearing member 31 and is normally retained in contact with the

collar 26 by a spring 35, as shown in Fig. 6. The latch 33 has a projecting end 36 adapted to be engaged by a trip 37 secured to the rail 1 at the inner end of the travel of the carriage *d*, simultaneous with the contacting of the carriage with a fixed abutment 38 on the frame 39 of the loom *a*.

The wire carriage *d* is moved in the direction to insert a pile wire into the open shed 10 of the fabric being woven, by an endless chain 25, adapted to sprocket wheels 40 and 41 rotatably mounted on studs secured in the frame 39 and the rail 1 respectively. A lug 42 integral with one link of the chain 25 is 15 adapted to engage the projection 28 of the collar 26.

The switch tongue 2 is grooved at 43 for the reception of the pile wire under control. A bar 44 is resiliently mounted in the groove 20 43 and is normally forced toward the wall 45 thereof by springs 46 for the purpose of keeping the pile wire straight and preventing horizontal flexing of the same.

To prevent or arrest the raising action of 25 the overhanging side of the plate 7 and the consequent vertical flexing of the pile wire under control, I provide brake structures 50 and 51.

The brake structure 50 comprises a vertically extending flanged bushing 52 secured to the plate 7 by screws 54. A rod 55 is mounted in the bushing and is free to slide axially thereof, having at its lower end a metallic shoe 56 rigidly secured thereto. The 35 shoe 56 is lined with suitable friction material 57 secured thereto and operatively engaging the underside of a longitudinally extending bar 58 secured at intervals throughout its length, adjacent the upper edge of the 40 rail 1, by screws 59. A heavy compression spring 60 is confined between the flange 53 of the bushing 52 and a retaining collar 61 adjustably held adjacent the upper end of the rod 55 by nuts 62-62. A second rod 63 45 is rigidly secured to the metal shoe 56 and extends vertically through an aperture in the plate 7, for the purpose of retaining the said shoe 56 in parallel relationship to the rail 1, at all times.

50 The braking structure 51 consists of a vertically extending bearing 64 having a cylindrical bore 65 and is internally threaded at its upper end to receive a tubular adjusting bolt 66. The bearing 64 has side flanges 67 55 rigidly secured to the vertical flange 14, of the plate 7, by rivets 68. Slidably mounted within the bore 65 is a shouldered rod 69, the lower or larger portion thereof snugly fitting the said bore 65, while the portion of 60 smaller diameter snugly fits the bore 70, of the tubular bolt 66. A compression spring 71 is confined within the bore 65 of the bearing 64 and between the shoulder of the rod 69, and the lower end of the hollow bolt 66, 65 which tends to force a shoe 72, on the lower

end of the rod 69, into contact with the upper face of one of the side walls of the rail 1. Friction material 73 is secured to the shoe 72 and engages the rail 1. A rectangular opening 74 is formed in the plate 7 to accommodate and guide the shoe 72-73.

The function of the braking elements 50 and 51 will be apparent, upon reference to Fig. 4, wherein the tendency of the plate 7, at its overhanging side, is to move downward and against the upper face of the switch tongue 2, using the edge of the bar 58 as a fulcrum. This action is extremely noticeable on looms wherein a perceptible amount of wear has occurred between the ribs 5 of the slide block 6 and the grooves 4 of the rail 1. They will also act to prevent overrunning of the carriage *d* when resistance to the movement thereof is relieved.

It is desirable to construct the pivot of the hook 8 in such a manner as to prevent it from becoming loose, in the plate 7, due to the suddenness with which heavy loads are applied thereto. The hook 8 pivots on a bushing 75 having a flange 76, between which 90 and the upper face of the plate 7 the hook 8 turns. A bolt 77 having a head 78 adapted to a counter bore 79 in the underside of the plate 7 is provided, which with the nuts 80-80 binds the bushing 75 rigidly to the 95 plate 7.

The sprocket wheel 20, distant from the frame 39 of the loom and around which the link belt 17 passes, is secured against relative rotation therebetween to a hollow shaft 100 85, as shown in Fig. 9.

The shaft 85 is journaled in the side walls 86 and 87 of a hollow extension 88 of, and integral with, the rail 1. An end wall 89 of said extension connects the side walls 86 and 87. One end of the shaft 85 is provided with projecting ears 90-90 adapted to grooves 91-91 in a jaw clutch member 92, adapted to slide axially off and on, and rotate with, the said shaft 85.

110 The clutch member 92 is secured, as at 93, to a rod 94 slidably mounted in the bore 95 of the hollow shaft 85.

Clutch jaws 96 on the clutch member 92 are adapted to engage clutch jaws 97 integral with a gear wheel 98 loosely mounted on the shaft 85, said gear 98 rotating on the shaft 85 between a collar 99 secured to said shaft and an extended bearing 100 on the wall 86.

115 The gear wheel 98 meshes with a gear wheel 101 rotatably mounted on the stud 41, said gear being rigidly secured to the sprocket wheel 20 adjacent thereto.

The shaft 85 is counterbored at 102 for the 125 reception of an enlargement 103 of the rod 94. A compression spring 104 surrounds the rod 94 between the enlargement 103 thereof and the base of the counterbore 102 and tends to move the rod 94 axially of the 130

shaft 85 and to move the jaws 96 of the clutch member 92 into engagement with the jaws 97 on the gear wheel 98.

The shaft 85 is transversely slotted at 105 3 for the reception of a retaining dog 106, which normally lies in contact with the rod 94 at a point adjacent the end of the enlargement 103 opposite to that engaged by the spring 104, for the purpose of maintaining 10 the clutch element 92 in an inoperative position with respect to the gear wheel 98.

The dog 106 is pivotally mounted at 107 (Fig. 11) on a split collar 108, loosely mounted on and angularly adjustable with 15 respect to the shaft 85 adjacent the side wall 87 of the extension 88. A clamping screw 109 is provided for the purpose of clamping the split collar 108, rigidly, in any position on the shaft 85 to which it may be adjusted.

20 A coiled spring 110 tends to force the dog 106 into engagement with the rod 94 at all times. The dog 106 is provided with a laterally projecting stud 111 on which is rotatably mounted a cam roller 112, for engagement 25 with a cam shaped end 113 of a lever 114.

The lever 114 is secured to one end of a sleeve shaft 115 rotatably mounted in the wall 87. On the opposite end of the sleeve 30 shaft 115 is secured a lever 116, provided at one of its ends with a roller 117 adapted to be engaged by a cam link 118 forming one of the side links of which the link belt 17 is composed. The opposite end of the lever 35 116 is provided with a limit screw 119 adapted to engage the upper side of the end wall 89 of the extension 88. A spring 120 tends to retain the screw 119 in contact with the top of the end wall 89, the cam lever 114 40 in an inoperative position (shown in broken lines in Fig. 11) and the cam roller 117 in a position to be engaged by the cam link 118.

The rod 94 has a second enlargement 121 thereon. A clutch release cam 122 is 45 mounted on said rod adjacent the outer end of said enlargement 121 and consists of a split collar 122 having a cam projection 123 thereon. The cam 122 is angularly adjustable with respect to the rod 94 and is adapted 50 to be retained in its adjusted position by means of a clamping screw 124.

A lever 125, having a cam projection 126 thereon which is movable into or out of a cooperating position with respect to the cam 55 projection 123, is secured to a shaft 127, one end of which is rotatably mounted in the wall 86 the opposite end thereof being rotatably mounted in a supporting bracket 128 secured to the wall 87. The side of the lever 125 opposite the cam projection 126 lies in 60 contact with the inside surface of the bracket 128. The shaft 127 is axially aligned with and passes through the sleeve shaft 115 and has secured to its end adjacent the wall 86 65 a lever 129.

One end 130 of the lever 129 is provided with a roller 131 for engagement with a cam link 132 forming one of the side links of the link belt 17, for the purpose of moving the cam end 126 of the lever 125 from its normal position (shown in broken lines in Fig. 12) to its operative position shown in dotted lines in Fig. 12. The opposite end 133 of the lever 129 is provided with a limit screw 134, adapted to engage the top surface of 75 the end wall 89 when said lever occupies its normal position, in which it is maintained by a spring 145.

The link belt 17 comprises centre links 136 on one of which is the projection 16; 80 side links 137 two of which, on opposite sides of the chain 17, are replaced by the cam links 118 and 132; and intermediate links 138 which are adapted to engage sprocket members 139—139 of the idler 85 sprockets 19. Centre sprocket members 140 engage the chain 17 in a manner similar to the sprockets 20—20 the sprocket member 140 however being cut away as at 141 for accommodation of the projection 16 as the chain 17 passes around the idler sprockets 19—19. This arrangement of elements is clearly shown in Figs. 16, 17 and 18.

The link belt 17 is supported along its upper run by an angle iron 146 secured to one side of the rail 1, to prevent sagging of said link belt and the consequent disengagement of the collar 26 and the projection 42 on said link belt.

In operation the wire carriage *d* is moved 100 outwardly from the loom proper by the link belt 17 in the usual manner to withdraw a wire, previously engaged by the hook 8, from the woven fabric. As the carriage and said engaged pile wire receive their initial movement outward, the overhanging side of the carriage tends to rise and with it the head end of the pile wire. Immediately after such initial movement the said raising tendency is arrested by the brake units 50 and 110 51 and the carriage is returned to a position wherein it engages the upper surface of the switch 2 and forces the pile wire downward into the bottom of the groove 43 wherein it is maintained throughout its 115 movement outward and inward.

Maintaining the pile wire in the bottom of the switch groove 43 insures its insertion into the open pile warp shed in a straight line, thus avoiding the fouling of the threads 120 of said open shed.

Immediately preceding the attainment of the extreme position in the outward travel of the carriage, *d*, the projecting end of the retaining lever engages the trip 21 and the dog 12 is thereby released from the projection 16 of the link belt 17, with a consequent stopping of the carriage *d* as illustrated in Figs. 8 and 11. The link belt 17 continues 125 its movement in an uninterrupted manner. 130

The wire switch 2 is then moved from its wire withdrawing position to its wire inserting position.

At the proper time, determined by the position of the cam link 118 on the link belt 17, the cam link 118 engages the roller 117, moving the cam end 113 of the lever 114 into engagement with the continuously rotating shaft 85 and into the path of rotation of the roller 112, which thereafter engages and rides up on the said cam end 113 with a consequent withdrawal of the retaining dog 106.

Withdrawal of the dog 106 from engagement with the enlargement 103 of the rod 94 permits the said rod 94 to be moved axially by the spring 104, with a consequent engagement of the clutch jaws 96 of the clutch element 92 with the clutch jaws 97 of the gear wheel 98 causing the same to be rotated with the shaft 85.

Rotation of the gear wheel 98, by reason of its meshing with the gear wheel 101 causes the said gear and the attached sprocket wheel 20 to rotate, thereby causing a movement of the link belt 25 in a direction opposite to the link belt 17 and at an increased speed thereto.

The lug 42 through its engagement with the projection 28 of the collar 26 which in turn is engaged by the latch 33, moves the carriage *d* and the previously withdrawn pile wire inwardly.

Immediately preceding the attainment of the extreme position in the inward travel of the carriage *d*, or just as the said carriage is about to contact with the fixed abutment 38, the projecting end 36 of the latch 33 engages the trip 37 thereby releasing the hook 32 thereof from the projection 27 of the collar 26 which releases the chain 25 from its load, any additional motion of the said chain, being absorbed by the spring 29 as the rod 24 is moved longitudinally, the said carriage contacting with the fixed abutment 38.

Simultaneous with the release of the hook 33 from the chain 25 the cam link 132 has engaged the roller 131 causing the cam end 126 of the lever 125 to be moved into a position between the inner side of the bracket 128 and the outer side of the cam collar 122. As the shaft 85 and rod 94 continue to rotate the cam projection 123 of said collar engages the cam projection 126 of the lever 125, with a consequent axial movement of the rod 94 against the action of the spring 104 until the outer side of the enlargement 103 passes the inner side of the dog 106 which promptly drops into the annular groove formed between the two enlargements 103 and 121, by action of the spring 110.

It will be understood that the cam link 118 moves from under the roller 117 and the elements controlled thereby return to their

normal positions, the operation of the dog 106 above described is thereby permitted.

The axial movement of the rod 94 releases the clutch jaws 96 from the jaws 97 causing the chain 25 to come to rest. Release of the clutch element 92 is accomplished with ease due to the fact that the load on the chain 25 is simultaneously released by the tripping of the latch 33 by the trip 37.

At this time the wire has been reinserted into the open warp shed which immediately changes and the hook 8 has engaged the next successive pile wire to be withdrawn. Due to the developed length of the link belt 17 and the speed with which the same has been moved in time with the other operating elements of the loom, the projection 16 now engages the dog 12 in the carriage *d* and moves the same outwardly. Henceforward the cycle of operations just described will be repeated.

It will be apparent from the above description that I control both the wire withdrawing and the wire inserting motions of the carriage *d* by mechanism of a positive operating nature and without the use of the unreliable friction clutch common to this type of loom.

It will also be apparent that I am able to avoid the flexing of the pile wire as it is inserted into the open warp shed so that it enters thereinto in a straight line and without fouling the threads forming said shed.

By the use of my invention, I eliminate the breaking of the pile wire heads from the wires, caused by the wire being misplaced when inserted into the pile warp shed and the head thereof being struck by the shuttle box, when the lay of the loom "beats up" the pile wire that has been misplaced in this manner.

As a precautionary measure against breakage of the carriage elements, in event of the carriage becoming jammed during its inward travel, the rigid coupling between the gear wheel 101 and the adjacent sprocket wheel 20, which consists of axially aligned apertures in said sprocket wheel and said gear wheel and a shear pin 150 adapted to enter said apertures, will be broken, permitting rotation of the said gear wheel 101 while the sprocket wheel 20 remains quiescent.

Many modifications may be made in the construction of my invention without departing from the essential features thereof, as for example: the carriage *d* may be secured to one endless chain and be reciprocated thereby, motion being imparted thereto at the proper time by mechanism controlled by a second continuous moving endless chain having cam links thereon, or by a continuously rotating cam wheel which may operate a clutch and controlling mechanism similar to that disclosed. I therefore

do not wish to limit my device to the exact construction shown in the drawings.

I claim:

1. The combination in a loom employing pile wires, of a reciprocating pile wire controlling carriage; endless link belts operatively movable in opposite directions for controlling the reciprocation of said carriage; and means on one of said link belts for controlling the operation of the other of said belts.
2. The combination in a loom employing pile wires, of a carriage for controlling the withdrawal of said pile wires successively and their reinsertion into the open warp shed of the fabric being woven; a rail power means for performing such withdrawing operation and power means for performing such reinserting operation; means co-operatively associated with said carriage and said rail for preventing distortion of said pile wire while undergoing said operations; and means for releasing the said power means from the carriage at the completion of each withdrawing and each reinserting movement of said carriage.
3. The combination in a loom employing pile wires, of a track; a reciprocating pile wire controlling carriage on said track; a wire switch adjacent said track; means carried by said carriage and engaging said track and tending to tilt said carriage laterally relative to said track and toward said switch for maintaining a portion of said carriage in contact with said switch throughout the reciprocation of said carriage; and means for reciprocating said carriage on said track.
4. The combination in a loom employing pile wires, of a reciprocating pile wire controlling carriage; a continuously driven link belt; an intermittently driven link belt associated with said carriage; means for actuating said intermittently driven link belt; means on said continuously driven link belt for controlling said actuation of the intermittently driven link belt.
5. The combination in a loom employing pile wires; of a reciprocating pile wire controlling carriage; a continuously driven link belt for moving said carriage in one direction, an intermittently driven link belt for moving said carriage in the opposite direction; means for actuating said intermittently driven link belt; means on said continuously driven link belt for controlling the actuation of said intermittently driven link belt; and means for disengaging the said carriage from the said link belts when said carriage attains the extreme position at each end of its reciprocation.
6. The combination in a loom employing pile wires, of a track; a pile wire controlling carriage reciprocally mounted on said track; a constantly driven link belt; a dog
- on said carriage, a retaining lever on said carriage and engaging said dog; a projection on said constantly driven belt designed to engage said dog and move said carriage in one direction, a trip on said track for disengaging said dog from said projection when said movement has been completed; an intermittently driven link belt; a latch on said carriage; a resiliently mounted collar on said carriage engaged by said latch; a projection on said intermittently driven link belt engaging said collar, for the purpose of moving said carriage in a reverse direction; a trip on said track for disengaging said latch from said collar when said carriage has completed said reverse movement; means for actuating said intermittently driven link belt, and means on said constantly driven link belt for controlling the said actuating means.
7. The combination in a loom employing pile wires, of a pile wire controlling carriage reciprocally mounted on a track; a constantly driven link belt; an intermittently driven link belt; a hollow shaft rotatably mounted in said track; a sprocket keyed to said hollow shaft around which the constantly driven link belt passes; a gear wheel loosely mounted on said hollow shaft; a clutch element on said gear wheel a gear wheel loosely mounted on said track and meshing with said first mentioned gear wheel, a sprocket secured to said second mentioned gear wheel, around which said intermittently driven link belt passes; a positive acting clutch element on said hollow shaft adapted to engage the clutch element on said gear wheel; means on said track for operating said clutch; and means on said constantly driven link belt for controlling said clutch operating means.
8. The combination in a loom employing pile wires of a reciprocating pile wire controlling carriage; and a link belt for controlling the reciprocation of said carriage, comprising centre links, and side links; projections on said centre links and projections on said side links for cooperative engagement with elements which control said reciprocation; and intermediate links for engagement with idler sprockets around which said link belt passes.
9. The combination in pile wire controlling mechanism for a loom, of a rail secured to the frame of said loom; a pile wire switch pivoted to said rail; a carriage slidably mounted on said rail; a bar secured to said rail; a braking structure mounted on said carriage and frictionally engaging the underside of said bar; a second braking structure mounted on said carriage and frictionally engaging the upper surface of said rail; means for reciprocating said carriage on said rail; and means for releasing said carriage from said reciprocating means at

the end of each completed stroke of the reciprocation of said carriage.

10. The combination, in pile wire controlling mechanism for a loom, of a rail; a pile wire switch having a groove; pile wires adapted to successively enter a groove in said switch; a carriage slidably mounted on said rail; a hook pivotally mounted on said carriage and adapted to select and engage the 5 said pile wires successively; means for reciprocating said carriage and the selected pile wire; means on said carriage and cooperatively engaging said rail for forcibly maintaining the said selected pile wire in the 10 bottom of said switch groove during the reciprocation thereof; and means for releasing the carriage from the reciprocating means at the completion of each stroke of the reciprocation of said carriage.

20. 11. The combination in pile wire controlling mechanism for a loom, of a rail; a grooved pile wire switch; pile wires "beat up" into the fabric being woven on said loom; a reciprocal carriage on said rail; a 25 hook on said carriage, for engaging said "beat up" pile wires successively; power means for moving the carriage outwardly along said rail; a trip on the rail for releasing said power means; bearings on said carriage; a rod in said bearings; a shoulder on said rod; a collar on said rod engaging said shoulder; a latch pivoted to said carriage; a hook on said latch normally engaging said collar; a spring for yieldably retaining said 30 latch in contact with said collar; an extension on said latch; a trip on said rail for engaging said extension; a spring surrounding said rod for returning the rod to its normal position in said bearings; and adjustable collars on said rod for retaining and 35 adjusting said spring on said rod.

12. The combination in pile wire controlling mechanism for looms, of a rail; a bar secured to said rail; a carriage slidably mounted on said rail; a flanged bushing secured to said carriage; a vertically slidable rod mounted in said bushing; a metallic shoe on the lower end of said rod; friction material secured to said shoe and engaging the 40 under side of said bar; a collar adjacent the upper end of said rod; retaining nuts adjustably mounted on said rod above said collar; a compression spring encircling said rod and confined between the flange of said bushing and the collar on said rod; a second braking structure on the carriage and engaging the upper surface of said rail; and means for reciprocating said carriage on said rail.

45. 13. The combination in pile wire controlling mechanism for looms, of a rail; a bar secured to said rail; a carriage slidably mounted on said rail; a braking structure mounted on said carriage and engaging the lower surface of said bar; a vertically extending flange on said carriage; a vertical-

ly extending bearing secured to said flange; a tubular bolt adjustably mounted in the upper end of said bearing; a shouldered rod slidably mounted in said bearing and said tubular bolt; a metallic shoe on the lower end 50 of said rod; friction material secured to said shoe; an aperture in said carriage through which said shoe passes into operative engagement with the upper surface of said rail; a spring encircling said rod and 55 confined between the lower end of said tubular bolt and the shoulder on said rod; a jam nut on said tubular bolt; and means for reciprocating said carriage on the rail.

14. The combination in pile wire controlling mechanism for a loom, of a rail; a grooved switch tongue adjacent said rail; a carriage slidably mounted on said rail and overhanging said switch; pile wires; a hook on said carriage for engagement with one of 60 said pile wires; a counterbored aperture in the overhanging portion of said carriage; a headed bolt adapted to said counterbored aperture; a bushing surrounding said bolt and positioned on the top of said carriage; 65 a flange on the said bushing between which and the said top of the carriage said hook is pivotally mounted; threaded nuts adapted to the upper end of said bolt by which said flanged bushing is rigidly secured to said carriage; power means for moving said carriage outwardly, whereby said hook will withdraw the engaged pile wire from the 70 fabric being woven; power means for moving said carriage inwardly to reinsert said wire into the open warp shed of said fabric; means for maintaining said pile wire in the bottom of the said switch groove during such movements of said carriage; and 75 means for instantaneously releasing said carriage from the reciprocating power means at 80 the end of its stroke in each direction.

15. The combination in a loom of a rail; a reciprocating wire controlling carriage; a link belt for moving the carriage outwardly on said rail; a shaft driven by said link belt; a gear wheel loosely mounted on said shaft; a clutch on said shaft cooperatively associated with said gear wheel; a gear wheel, loosely mounted on a stud extending 85 from said rail, and meshing with said first mentioned gear wheel; a sprocket wheel loosely mounted on said stud adjacent said second mentioned gear wheel; a second link belt on said sprocket for moving the said carriage inwardly on said rail; axially aligned apertures in said second mentioned gear wheel and the adjacent sprocket wheel; and a replaceable shear pin adapted to said 90 apertures for rigidly securing said sprocket and said gear wheel together and acting as a safety element against breakage of the other elements in event of the jamming of said carriage on said rail.

16. The combination in a loom employing 95

pile wires of a reciprocally mounted wire controlling carriage; means for reciprocating said carriage including a driving shaft and a clutch element thereon; and safety means associated with said carriage reciprocating means including a pin passing through said shaft and said clutch element

and adapted to be sheared by relative movement therebetween for the purpose of preventing the breakage of any of the other 10 of said elements due to abnormal loads being applied thereto.

WILLIAM E. SMITH.
